L. MAYER.

THISTLE ERADICATOR.

APPLICATION FILED JAN. 23, 1920.

1,358,323.

Patented Nov. 9, 1920.

Fig. 1.

UNITED STATES PATENT OFFICE.

LOUIS MAYER, OF KAUKAUNA, WISCONSIN, ASSIGNOR TO KAUKAUNA MACHINE WORKS, OF KAUKAUNA, WISCONSIN, A CORPORATION OF WISCONSIN.

THISTLE-ERADICATOR.

1,358,323.

Specification of Letters Patent.

Patented Nov. 9, 1920.

Application filed January 23, 1920. Serial No. 353,562.

To all whom it may concern:

Be it known that I, LOUIS MAYER, a citizen of the United States, and resident of Kaukauna, in the county of Outagamie and State 5 of Wisconsin, have invented new and useful Improvements in Thistle-Eradicators, of which the following is a description, reference being had to the accompanying drawings, which are a part of this specification.

10 The present invention relates to certain new and useful improvements in thistle eradicators and has for one of its objects to provide positive means carried by each comb member of the eradicator for cleaning the 15 same after each complete revolution.

Another object of the present invention is to provide comparatively simple but efficient means for adjusting the comb members of the eradicator with respect to the surface of 20 the ground over which my device is operated.

A further object of the present invention is to provide improved means for operatively connecting and disconnecting the comb carrying gear and the main drive gear 25 of the eradicator.

A still further object of this invention is to provide a thistle eradicator of simple construction and light weight, and at the same time efficient in operation.

30 With the above and other objects in view which will appear as the description proceeds, my invention resides in the novel construction, combination and arrangement of parts substantially as hereinafter described 35 and more particularly defined by the appended claims, it being understood that such changes in the precise embodiment of the herein-disclosed invention may be made as come within the scope of the claims.

40 In the accompanying drawing I have illustrated one complete example of the physical embodiment of my invention constructed according to the best mode I have so far devised for the practical application of the 45 principles thereof, and in which:

Figure 1 is a side elevation of the machine, the wheel next the observer being removed, and parts broken away to more clearly illustrate details of construction.

50 Fig. 2 is a sectional view taken through

the comb members illustrating my improved manner of operating the comb cleaning bars.

Fig. 3 is a fragmentary perspective view 55 illustrating the means I employ for adjusting the elevation of the comb members and for moving the comb carrying side arms horizontally to engage and disengage the comb driving gear from the main gear, said view having parts broken away and in section.

60 Fig. 4 is a fragmentary perspective view of the means I employ for maintaining the comb gear and the drive gear in either operative or inoperative engagement, and

Fig. 5 is a fragmentary perspective view 65 of one of the comb members and the cleaner bar arranged there adjacent to clean the teeth thereof.

70 My invention may be said to consist broadly of wheel means having a comb carrying frame mounted thereon, gear means for drivingly connecting the comb carried by said frame with a driven axle, means for moving the side members forming said frame horizontally to connect and disconnect 75 said gears, comb cleaning members having means for positively moving the same along the comb surface once every revolution to clean foreign matter therefrom, and means for adjusting the outer end of said frame to 80 position the comb members with respect to the ground.

75 My device is supported by means of two complementary wheels 10 revolvably journaled on shaft spindles 11 carried by a main axle member 12, the axle 12 having thills 13 secured thereto in any desired manner. The thills 13 are connected by means of a transverse member 14 forming a frame with the axle 12 on which is supported a driver's 90 seat 15. Journaled on the spindles 11 inward of each wheel 10 is a bearing block 16 having its elongated end adjustably secured to a side arm 17 forming a part of a comb carrying frame by means of a bolt 18.

95 The side arms 17 are each provided with two horizontal aligned elongated apertures 19 and 20 through which pass the axle spindle 11 and bolt 18 respectively. This structure permits the outer free end 21 of 100

each side arm 17 to be moved toward or away from the axle spindle 11, and this horizontal movement of the side arms 17 is controlled by means of a rod or shaft 22 journaled in bearing brackets 23 carried by the axle 12 and having its ends cranked as at 24 and engaging in curved recesses 25 in the side arms. The shaft 22 is rotated by means of a hand lever 26 and is adapted to be held 10 in either one of two adjustments, one with the end 21 of the side arm 17 spaced from the axle and vice versa, by means of a bracket member 27 having notches 28 therein in which the lever 26 is selectively engaged. This movement of the side arms 17 is effective to engage and disengage the driving gears to be later described.

Secured to each side arm 17 near its outer free end 21 is a bearing member 29 in which 20 the ends of a shaft 30 are revolvably mounted. Splined on the shaft 30 in spaced relation are reel heads 31 each consisting, in the present instance, of three arms 32 and the adjacent arms of each reel head are connected by means of transversely extending brace bars or angle irons 33 to which a comb 34 is secured as at 35. As best shown in Fig. 5, the comb 34 is formed with a plurality of tines or teeth 36 adapted to catch the blossoms and heads of thistles and the like and to either cut or break the blossoms and heads off or to pull the same up out of the ground so that the thistles can not perpetuate themselves from their ripened seeds.

35 The shaft 30 and with it the reel heads and combs, is adapted to be rotated from one of the wheels 10, and one end of the shaft 30 has splined thereto a gear pinion 37 adapted to be meshed with a main drive 40 gear 38 freely journaled on the adjacent spindle 11 and rigid with the adjacent wheel 10 (not shown). With the lever 26 in the position depicted in Figs. 1 and 4, the gears 37 and 38 will be in mesh and when the 45 wheel 10 carrying the gear 38 is rotated the combs will be rotated in the direction of the arrow in Fig 1 and when the lever 26 is engaged in the other notch 28 the gears will be out of mesh and the revolution of the 50 gear 38 will not impart any movement to the combs.

In order to clean the thistle heads and other foreign matter from between the tines of the combs after they have completed one 55 revolution and are about to again engage with the thistle heads, I provide means for sweeping the comb teeth to remove such foreign matter therefrom. This means consists of a bar 39, preferably of angle iron and adapted to engage the inside of each comb as best shown in Figs. 1, 2 and 5. The bar 39 has its ends secured to the outer ends of the long arms 40 of L shaped levers 41 each pivoted as at 42 to the arms 32 of the

reel heads and having a friction roller 43 65 journaled in the outer end of its short arm 44 for tracking in a cam-way groove 45 formed in each bearing block 29.

As best shown in Fig. 2 the projection or cam 46 of each cam block forces the friction roller 43 away from the shaft 30 when the same reaches a position approximately that shown in Fig. 2, when the outer end of the long arm 40, and with it the cleaner bar 39, will be moved to a position adjacent the outer ends of the comb teeth removing therefrom all foreign matter. When the roller passes beyond the cam 40 the same will be moved toward the shaft 30 by means of the outer flange 47 of the cam to force the outer 80 end of the arm 40 in toward the base of the comb teeth and the same is thus inoperative until the roller 43 again engages the cam 46. As will be understood a comb cleaning bar is arranged adjacent each comb as best 85 shown in Fig. 2.

The combs are adapted to be adjusted vertically to arrange them at various heights with respect to the ground and this is accomplished by means of a journaled shaft 90 48 disposed above the axle 12 and having rearwardly extending crank arms 49 connected to each side arm 17 by means of link members 50. The shaft 48 is adapted to be rotated by means of a hand crank 51 operating a worm gear 52 in mesh with a segmental gear 53 fixed to the shaft 48. As will be obvious when the outer ends of the cranks 49 are raised the distance between the combs 34 and the ground will be increased and when they are lowered the distance will be decreased.

What I claim as my invention is:

1. A device of the class described comprising a frame, a revolvably mounted comb carrying head supported by the frame, a comb carried by said head, a lever including a long and a short arm arranged at an angle, means pivotally securing said lever to the comb carrying head at the apex of the angle 11 formed by the long and short arms, a cleaning bar for said comb and arranged to sweep the same, means connecting the outer end of one of the arms of said lever with the cleaning bar, a cam track-way, means on 11 the outer end of the other arm of said lever for tracking in said cam-way, and means for revolving said comb carrying head, said cam track-way being so shaped and positioned that the outer end of the arm of said lever 120 connected with the cleaning bar will be moved to a position adjacent the outer end of the comb once every revolution thereof.

2. A thistle eradicator comprising a frame, a revolvably mounted comb carried thereby, a substantially L shaped lever pivoted at its apex and having a long and a short arm the outer end of the long arm of

the L being positioned adjacent the inner face of the comb, a comb cleaning bar arranged to move along the inner face of the comb and secured to the outer end of said long arm of the L shaped lever, a cam track-way, roller means journaled in the outer end of the short arm of said L shaped lever and tracking in said cam-way, and means for re-

volving said comb, said track-way being so shaped and positioned that the outer end of the long arm of said L shaped lever will be moved to a position adjacent the outer end of the comb once every revolution thereof.

In testimony whereof, I affix my signature.

LOUIS MAYER.
